1

This invention relates to methods of, and machines for, combing cotton and other textile fibres.

Objects of the invention are to provide combing machines which are capable of greatly increased production and which provide a better combed, and a more equal product. A further object is to provide combing machines which are of simplified construction and operation and which are considerably less bulky and occupy much less space than known machines.

Some advantages of the present invention are:

Large production: the feeding of a much thicker lap than hitherto usual, is possible, the machine runs continuously and the time for changing from long to short cotton, or vice versa, is reduced to a few minutes.

Perfect combing: the best possible elimination of impurities is achieved by combing thoroughly both ends of the tuft beyond the middle of its length, the combing of short cotton is possible.

Strong product: little strain is imposed on the fibres during the detachment and combing, and because of the preliminary combing few of the valuable long fibres are lost.

Perfect regularity: the regularity of the combed lap is equal to the regularity of the fed lap.

Less preparatory machinery necessary: because of the regularity of the combed lap, less doubling and therefore less subsequent machinery is necessary and a drawing mechanism can be mounted on the machine before, and after the combing operations.

Other advantages: The machine is simple and robust in construction; on the same production it occupies less space and requires less power to drive than known combers.

According to the present invention, I provide a method of and machine for combing cotton and other textile fibres, in which tuft-holding means are moved continuously and uninterruptedly around stationary combing means and which include one pair, or spaced pairs, of rollers, or equivalent rotatable members having curved cooperating peripheries, turnable about their own axes to grip the tuft and move it relatively to the nip of the rollers or equivalent members, the operative association of the two members of the, or each, pair of rollers or equivalent rotatable members, or the operative association of the two members of the pair with at least one other pivoted member included in said tuft-holding means, being used to grip, take the tuft from a lap, move it past the combing means and release it to delivery means, the rollers or equivalent members being inverted while the tuft is being moved past the

combing means so that both ends of the tuft are presented to the combing means during the time that the tuft holding means are being moved from the position in which the uncombed tuft is removed from the lap to be combed to the position in which the combed tuft is overlapped on the lap of previously combed fibre, the tuft holding means also being caused to approach the combing means in order that the ends of the tuft shall be presented to the combing means for combing and also to move away from the combing means after one end of the tuft has been combed.

The expression "stationary combing means" means that the combing means is stationary as a unit while combing and does not exclude combing means which are adjustable in order that the position of the combs can be varied to suit requirements.

As the combing means are arranged on one side only of the path of movement of the tuft-holding means the inversion of the tuft is necessary after one end has been combed so that the opposite end can also be presented to the combing means. By inverting the tuft is meant turning the rollers or equivalent members through a predetermined angle as a unit so that the leading member thereof and the leading or combed end of the tuft becomes the trailing member and end respectively.

Modified methods and machines according to the invention, particularly adapted to be used in the combing of relatively short-stapled textile fibers, are characterised by the feature that after the tuft has been detached from the lap of uncombed fibres and then moved by a pair of cooperating, relatively turnable rollers, it is either held between one of said rollers and a single nipper means, or between two relatively movable nipper means, which means are operatively associated with the pair of rollers and are moved with them along the combing means, the nip of one of the rollers and the nipper means, or the nip of the two nipper means, being caused to approach the combing means and to remain in relatively close proximity to them throughout the combing operation and then to recede from the combing means. By these methods and machines the tufts are either gripped at a position on the periphery of one of the rollers of the pair of rollers, or at a position between the two nipper means, both of these positions being nearer to the combing means than the line of contact of the pair of rollers so that much shorter fibres can be combed.

In one method of and machine for combing cotton and other textile fibres according to the pres-

2

55

ent invention, use is made of combing means mounted on a normally stationary combing cylinder or segmental support. In this method and machine the operations of gripping the end of the uncombed lap, detaching the tuft from the lap of uncombed fibres, causing the leading end of the tuft to be presented to the combing means, combing that end of the tuft, inversion of the tuft, causing the opposite trailing end of the tuft to be presented to the combing means, combing of the trailing ends of the tuft, and overlapping of the completely combed tuft on the lap of combed fibres are all carried out by means including pairs of cooperating, rotatable rollers which act to ensure or to assist in ensuring that all the operations shall be carried out while the rollers are making one revolution around the combing cylinder or segmental support.

Constructional forms of the invention are shown, by way of example, on the accompanying sheets of drawings, whereon—

Fig. 1 is a side elevation, partly in section, of the machine, the rear frame member of the machine, the rear disc, the rear bearing boxes for the tuft-holding rollers, their supports and the rear pin-carrying discs being omitted from the figure;

Fig. 2 is a front view of part of the revolving drum and the feeding and delivery drums with the front frame and driving pulley and wheel omitted;

Fig. 3 is a sectional view taken on the line A—A of Fig. 1;

Fig. 3a is a section taken on the line B—B in Fig. 1;

Fig. 4 is a fragmentary view of the rear frame of the machine and shows diagrammatically the movements of one pair of tuft-holding rollers from the delivery drum to the feeding drum and around one of the segmental comb sets to the top end of the other segmental comb set;

Fig. 5 top, is a diagrammatic view showing the movements of a pair of tuft-holding rollers and the manner of presenting the tuft to the two segmental comb sets;

Fig. 5, left bottom, and Figs. 6 to 9, diagrammatically show the action of the roller which operates to press the uncombed lap onto the feeding drum while a pair of tuft-holding rollers is detaching the tuft from the lap;

Fig. 5, right bottom, and Figs. 10 to 13, diagrammatically show the action of the roller which acts to overlap the combed tuft upon the lap on the delivery drum.

Fig. 14 is a diagrammatic view showing the guide slots formed in one of the end frames of a modified machine in which two guiding pins only are carried upon the shafts of the tuft-holding roller bearing boxes, and in which also the said shafts are caused to run in guide slots in the frames, each shaft following the path indicated by the chain-dotted line in the figures;

Fig. 15 is a diagrammatic view showing the movements of a pair of tuft-holding rollers and a nipper bar associated therewith in the modified machine referred to above.

Fig. 15A is a diagrammatic view of a modified arrangement in which two nipper bars are associated with each pair of rollers;

Figs. 16 and 17 are fragmentary sectional views of an alternative method of supporting the cooperating tuft-holding rollers in their bearing boxes and driving the rollers positively;

Fig. 18 is a plan view of a locking plate used in association with the arrangement shown in Figs. 16 and 17;

Fig. 19 is a fragmentary sectional view of the upper part of one end of a modified machine including means for positively driving the rollers and the arrangement for guiding the rollers as shown in Fig. 14;

Fig. 20 is a section of a detail of the modified machine shown in Fig. 19; and

Fig. 21 is a fragmentary diagrammatic view showing an alternative method of turning the tuft-holding rollers in the required directions, such turning movements being carried out positively.

Referring first to Figs. 1 to 13—

The combing cylinder 1, the section of which is less than a complete circle, is fixed on a stationary tubular shaft 2, see Figs. 1 and 3. At the front of the combing cylinder 1 is a disc 3 formed with a hollow hub 4 which is adapted to revolve on the shaft 2 and in a main bearing 5 provided in the front frame 6 of the machine. The hub projects through the bearing 5 and on it are fixed a driving pulley 7 and a toothed wheel 8. At the rear of the combing cylinder, a disc identical with the disc 3, is turnably arranged upon the shaft 2 and in a bearing, corresponding to the front bearing 5, provided in the rear frame of the machine. The rear disc, the rear hub and the rear frame are not shown on the drawings.

The front disc 3 and the corresponding rear disc are connected by three arcuate plates 9, external to the combing cylinder 1 as shown in Figs. 1 and 3 and forming a carrier member coaxial with the comb support.

Three pairs of parallel tuft-holding rollers 10 and 11 are arranged to travel around the combing cylinder 1 and at least one or the other of the rollers 10 and 11 is provided with an elastic covering such as leather, or cloth, rubber-cot or the like. Each roller 10 is provided with a toothed wheel 12 at its rear end and with two loose collars 13a and 13b at its opposite ends. Each roller 11 carries a toothed wheel 14 at its front end. The journal ends of each pair of rollers 10 and 11 are arranged in slots 15 formed in members or bearing boxes 16 which are arranged at opposite ends of the machine. Fig. 1 shows the front bearing box 16 with its slot 15, see also Fig. 3, which shows the rear bearing boxes, and parts of the means or cross pieces 17 which connect the front and rear bearing boxes.

Referring to Figs. 1 and 3a, it will be seen that the journal parts of the rollers 10 and 11 are resiliently pressed towards each other by means of a coil spring fitted between a set screw screwed through the outer wall of the bearing box 16 and another set screw screwed through the inner wall. The spring acts upon the bearing pad 13c which bears on the journal end of the roller 10 and the last mentioned set screw presses against a bearing pad 14a which bears against the journal end of the roller 11. The rollers are thus held in a required position within the slots 15 in such a way that the rotary movement of one is communicated to the other and so that they can slide in the boxes. Each end of the bearing box 16 is integral with a shaft 18 turnably supported in a boss 19 formed on a supporting member or bar 21, see also Fig. 2, which is arranged to slide radially in a guide slot 21a formed in a guide member 22 fixed on the outer face of each of the discs 3. As shown in Figure 2, the three guide members 22 are spaced equidistantly around the axis of the front and rear discs 3. Fixed at each end of each shaft 18 on the outside of each of the bosses 19 is a turnable member or disc 20

provided with four equidistantly-spaced pins P, R, S and T projecting towards the adjacent frame 6.

Thus, spaced equidistantly around the shaft 2 there are three pairs of rollers 10 and 11, each pair being adapted for rotational movement around the shaft 2 and for radial movement towards and from the axis of the shaft 2. Each roller is adapted to turn about its own axis and both rollers can turn in company around the axes of the shafts 18 and can move in the longitudinal direction of the slots 15 in the front and rear bearing boxes 16.

The movements of the rollers 10 and 11 around the axes of the shafts 18 and radially are, as described hereinafter, carried out by the cooperation of the pins P, R, S and T (which travel with the discs 20 around the combing cylinder 1) with guiding means provided on the front and rear frames 6.

The pins P, R, S and T are equidistantly spaced on a circle having its centre on the common axis of the shafts 18 at the front and rear of each box 16. In the position shown in Figs. 1 and 3, the plane passing through the longitudinal axes of the opposed front and rear slots 15 and the plane passing through the axes of the pins R and T are coincident.

The movements of the rollers of each pair of rollers 10 and 11 around their axes are carried out by the following means. At suitable spaced positions on the front and rear end walls of the stationary combing cylinder 1 there are two toothed segments 23 and 24 respectively, Figs. 1 and 3, adapted to turn around bolts 25 whereby they are mounted upon the end walls.

The toothed segments are held in the positions shown in Fig. 3, by means of springs 26. When the rollers 10 and 11 are moving around the combing cylinder 1, the toothed wheels 12 and 14 respectively engage with the toothed segments 24 and 23 as described hereinafter, the springs 26 preventing the breaking of the teeth which might otherwise occur.

As shown in Figs. 1 to 3, situated below the combing cylinder 1 there are two drums 27 and 46 covered with elastic material, such as leather on cloth, rubber-cot or the like, the drum 27 being the feeding drum and the drum 46 the receiving or delivery drum.

The drum 27 is fixed to a shaft 28 which rotates in bearings provided in front and rear pedestals 29, a ratchet wheel 30 and a toothed wheel 61 also being fixed on the shaft on opposite sides of the front pedestal, and a toothed wheel 62 is fixed on the shaft at the rear of the rear pedestal. A pulley 31, to which is attached a belt, carrying a weight 32 indicated by the arrow in Figs. 1 to 3, is adapted to rotate about the bearing boss of the rear pedestal 29, the weight tending to turn the pulley in the clockwise direction as viewed in Figs. 2 and 3.

Fixed to the pulley 31 is an arm 33b connected by a cross member 34 to an arm 33a loosely mounted on the shaft 28 at the rear of the ratchet wheel 30. Aligned slots 35a and 35b are formed in the arms 33a and 33b respectively, and these slots serve as bearings for the journal ends of a roller 36. The roller is pulled by a spring (not shown) in a radial direction, so that it exerts pressure on the drum 27. If either the pulley 31 or the roller 36 is moved, then both the roller and the pulley move.

A cam 37, see Figs. 1 to 3, is loosely mounted upon the rearwardly-extending hub of the arm 33a, and is adapted to be rendered stationary

thereon by means of a laterally-extending arm 38 formed with a slot 38a. The arm lies against a stationary bracket 39, Fig. 2, formed with a slot 39a and, by means of a bolt 38b, which extends through both slots, the arm 38 can be fixed in a higher or lower position and thus the angular position of the rise 40, Fig. 3, of the cam 37 can be altered.

A pin 41, fixed to the arm 33a and projecting forwardly therefrom carries a pivoted pawl 42 adapted to cooperate with the ratchet wheel 30. Another pin 43, parallel to the pin 41, is fixed to the pawl 42 and extends rearwardly across the bar 33a. The pin 43 carries a turnable roller 44, which is adapted to ride on the cam 37 and is drawn towards the axis of the drum 27 by spring means (not shown). Parallel to the shaft 28 and bearing on the surface of the drum 27 is a roller 45 arranged on a fixed axis.

The delivery drum 46, Figs. 2 and 3, is fixed to a shaft 47 which is parallel to the shaft 28 and is rotatably mounted in bearings provided in front and rear brackets 48. The drum 46 and its associated parts, viz., the turnable front and rear arms 49a and 49b, the cross member 50, the roller 36a, the cam 51 and its integral arm 52 formed with a slot 53, the pulley 31a and its weight 32a are identical with the drum 27 and its corresponding associated parts. It will be seen from Fig. 2, that the arm 52 lies against the back of the bracket 39 and that a bolt 53a passing through the slots 39a and 53 serves to fix the cam 51 and its rise 54 in their angularly-adjusted positions. A ratchet wheel, corresponding to the ratchet wheel 30, is not provided on the shaft 47 and, moreover, an arm 55 is pivotally mounted on a pin 56 fixed to the front arm 49a. A pin 57 is fixed to the arm 55 and carries a turnable roller 58 which runs upon the cam 51. A roller 65, Fig. 3, parallel to the drum 46 is adapted to bear on the surface of the latter.

The shaft 28 is driven from the pulley 7 by means of a train of gears consisting of the toothed wheels 8, 59, 60 and 61. By altering the gear train the speed of the drum 27 in relation to the main drive can be altered to suit the staple of the fibre being combed. A toothed wheel 62 is fixed on the rear end of the shaft 28 (Figs. 1 and 3) and through a wheel 63 drives a toothed wheel 64 mounted on the shaft 47 of the drum 46 (Fig. 3). By changing the wheels 62 or 64 the relative speeds of the drums 27 and 46 and the length of the overlap of the combed fibres on the combed lap can be altered.

Referring to Fig. 4 in order to make the subsequent description of the operation of the machine quite clear, the mechanisms for operating the different movements of the rollers 10 and 11 will now be described independently of the general operation of the machine.

The various movements of the three pairs of rollers 10 and 11 as they travel around the combing cylinder 1 are controlled partly by the cooperation of the pins P, R, S, T carried on the said discs 20, mounted at the opposite ends of the shafts 18, with guide slots or recesses and guide surfaces provided on the inside of the front and rear frame members 6 of the machine. The guide slots or recesses and guide surfaces on the front frame member are identical with those on the rear frame member, so that it will only be necessary to describe the cooperation of the pins P, R, S, T on one of the discs 20 with the guide slots or recesses and guide surfaces on the adjacent frame member. Fig. 4 shows diagrammati-

cally the formation and the disposition of the guide slots and surfaces on the rear frame member, the surfaces being cross hatched.

Fig. 4 also shows diagrammatically the movements of one pair of rollers 10 and 11 in different positions, while the rollers are travelling around the combing cylinder 1 in the clockwise direction.

The disc 20 at the rear end of the shaft 18 is indicated by a cross formed by connecting the centres of the pins P and S and R and T and the index numerals added to the reference letters, P, R, S, T indicate the position number referred to in the description.

The paths traced by the centres of the front and rear discs 20 are shown by means of a chain dotted line at each point on this line and, while the machine is operating, the centre of a disc 20 is carried by discs 3 in the direction of a tangent of a circle, the centre of which is the centre M of the combing cylinder 1.

The centres are prevented from following this tangential direction by at least two of the pins P, R, S, T being guided in guiding means provided for them in the frame members.

When the discs 20 are in the position 0, the pins T rest in the bottom of guide slots 70 and the pins P in curved recesses 71, the common centres of the recesses 71 being coaxial with the feeding drum 27. As the discs and plates 3, 9 rotate, the tangential movement causes the discs 20 to swing around the pins P. The axis of the discs travels through a curved path which is concentric with the drum 27. The engagement of the pins T in their guides 70 direct the pins S towards the guide surfaces 72a along which they are guided until they reach the position 1, eventually engaging in the curved guide slot 72.

As already described, the journal ends of the rollers 10 and 11 are movable in the slots 15 in the bearing boxes 16 and they are held therein as shown in the different positions of Fig. 4, that is to say, with the axis of the roller 10 nearer to the axis of the discs 20 than the axis of the roller 11. Thus, the distance from the pins P to the roller 10 is smaller than from the pins P to the roller 11. While moving from the position 0 to the position 1, therefore, the axis of the roller 10 follows a curved path having a smaller radius than the curved path followed by the axis of the roller 11. The effect of this is that if the rollers are set correctly, within the slots 15, the roller 10 is pressed on to the feeding drum 27, while the roller 11 scarcely touches it. When moving from the position 0 to the position 1, the contact of the roller 10 with the drum 27 causes the roller to revolve in the anti-clockwise direction on its axis and as the roller 11 is held in resilient contact with the roller 10, it will revolve in the clockwise direction.

As the discs 20 are moved from the position 1 onwards towards position 2, the rollers 10 and 11 are moved further away from the drum 27, the pins S being guided in the guide slots 72 and the pins P sliding on guide surfaces 73. Shortly after the discs 20 have passed position 2, the rollers 10 and 11 reach a position in which the extension of the line connecting the pins P and S passes through the centre M of the combing cylinder 1. This position, which, hereinafter, will be called the "combing position," is vacated only after position 5 referred to below has been reached.

Before the discs 20 reach the position 3, the teeth of the wheel 14 on the roller 11 engage with the teeth of the segment 23 and the rollers 10 and 11 are caused to revolve in opposite di-

rections, as shown by the arrows on the roller 10 and gear wheel 14 in Fig. 4. In position 3 this revolving movement of the rollers is almost completed. When the discs 20 are in position 3, the pins R are guided by curved guides 74 and the pins S, which have moved out of the guide slots 72, are guided by curved guides 75 concentric with the combing cylinder, and these pins continue to be guided by the guides shortly after position 4. Shortly before the discs 20 reach position 4, however, the pins T are also guided by the curved guides 74. In due course the pins R run off the guides 74 but the pins T and S continue to run on the guides 74 and 75 until the discs 20 reach position 5.

Before the discs 20 reach position 5, the pins P, after having left the surface guide 73, and after having moved concentric to the combing cylinder, enter guide slots 76 in which they travel until they lodge in the peaks 76a. The pins remain in the peaks 76a until the discs 20 reach the position 6, the discs and the pins R, S, T swinging around the pins P. During this swinging movement, the pins T are guided by the curved guides 77 and the pins R make their way upwardly into tapered guide slots 78, eventually lodging in the peaks 78a thereof. As the discs 20 continue their movement, they swing around the pins R engaged in the peaks 78a, the pins P being guided downwardly in the slots 76 until eventually, the pins S engage in the guide slots 79, in which they travel upwardly until they lodge in the peaks 80.

As the guide slots and guide surfaces on the right hand side of the vertical plane in Fig. 4 passing through the axis M of the combing cylinder are identical with those on the left hand side of the plane, it is clear that the right hand path of the disc centre will correspond exactly to the left hand path. It is unnecessary, therefore, to describe the movements on the right hand side in detail, as the succeeding movements of the discs 20, and the pins P, R, S, T around the combing cylinder correspond to the movements described above, except that the roller 11 leads the roller 10, since the discs 20 have been turned through 180 degrees. The movement such as from position 5 to 7, where this takes place will hereinafter be referred to as the "inversion movement."

When the disc 20 are in position 7, the rollers 10 and 11 have returned to the combing position, and, moving further in the clockwise direction, the teeth of the wheel 12 on the roller 10 mesh with the toothed segment 24, see Figs. 3 and 4, whereby partial revolution of the roller 10 takes place in the clockwise direction.

When the rollers 10 and 11 eventually reach position 8 (Fig. 4) they are moving around the receiving drum 46 as described in connection with the movement of the rollers around the feeding drum 27. The roller 10 rotates in the counter-clockwise direction on the drum 46, while the roller 11 scarcely touches it.

When the discs 20 have reached position 8, the pins S are engaged in guide recesses 81 and the discs swing about these pins with the pins P running in contact with the guide surfaces 82. In due course, the pins T re-engage in the guide slots 70 (position 0) and the pins P re-engage in the guide recesses 71. The rollers are thus inverted and the roller 10 again leads the roller 11 when it contacts with the surface of the feeding drum 27.

Referring to Figs. 5 to 13, the general operation of the machine will now be described.

The arcuate arrows inside the rollers indicate the direction of rotation of the rollers around their own axes, and the radial arrows inside the rollers indicate that rollers are not revolving around their axes.

The rollers 10 and 11 take a part in every operation and the complete operation of the machine can be understood most easily by following the movement of a pair of rollers around the combing cylinder 1.

Detachment of the tuft of fibres

In Fig. 6, the rollers 10 and 11 are shown in a position corresponding to position 0 in Fig. 4. Owing to the action of the weight 32, the roller 36 moves at the speed of the drum 27 towards the rollers 10 and 11. The arms 33a and 33b are prevented from reaching a greater speed than the drum 27 (which is turning in the same direction) by means of the pawl 42, which is held by a tooth of the ratchet wheel 30. While moving towards the rollers 10 and 11, the roller 36 presses upon the drum 27, the fibre ends 84 of the fibrous sheet or lap 83, which has been opened in known manner, the fibres lying substantially parallel. As shown in Fig. 6 the lap 83 has reached the feeding drum 27 underneath one or more calender rollers 45 turnable on fixed axes.

While rolling on the drum 27 in the counter clockwise direction, the roller 10 and its collars 13a and 13b, see Fig. 1, come into contact with the arms 33a and 33b and push them against the direction in which they try to turn. The pawl 42 springs over the teeth of the ratchet wheel 30 and is lifted away from the latter by the roller 44 when the latter rides on the rise 40 of the cam 37 as shown in Fig. 7. Meanwhile, the roller 36 rolls on the top of the lap 83, the end 84 of which passes underneath the roller 10 and is seized between the counter-rotating rollers 10 and 11. Any fibres which may stick to the drum 27 are stripped off by the roller 11 and led to the rest of the fibres. In the position shown in Fig. 8, the rollers 10 and 11 terminate their movement on the drum 27 and they cease to rotate around their axes when they leave the drum 27. The lap 83 is firmly held between the rollers 10 and 11 and its end 84 partly protrudes from the nip of the rollers.

The rollers 10 and 11 move further from the drum 27, and finally move out of the way of the arms 33a and 33b and of the roller 36. As the latter still tries to move in the clockwise direction, owing to the action of the weight 32, it causes a steady pressure to be exerted on that part of the lap 83 which is held under the roller 36 and between the rollers 10 and 11, see Fig. 9. As long as the end of the lap up to the nip of the roller 36 is shorter than the staple length the fibres held between the rollers 10 and 11 and the roller 36 resist a movement of the latter in the clockwise direction.

Moving still further from the drum 27, the rollers 10 and 11 draw all the fibres (i. e., the tuft) held between them in its reach. The roller 36, pressing steadily on the lap 83 and in the opposite direction to that in which the tuft is moving, prevents fibres from the lap 83 being taken along with the tuft. Thus, a neat and clean separation of the tuft is obtained, when position I, Fig. 5, is reached. In this position, the lap 83, held by the roller 36 on the drum 27 projects from under the roller in the form of a tuft 84a.

As they are now freed from all restraint, the arms 33a and 33b move in the clockwise direction at a greater speed than the drum 27 and the roller 36 successively presses the tuft on the drum 27, until it reaches the ends of the fibres. The rise 40 of the cam 37 must be set in such a position that it causes the roller 44 to descend and the pawl 42 to fall between two teeth of the ratchet wheel 30 at the moment when the roller 36 reaches the end of the said fibres. Thereafter, the arms 33a and 33b and the roller 36 travel at the speed of the drum 27, until the initial position (Fig. 6) for the detachment of a tuft is again reached.

The detachment of the succeeding tuft, carried out as described above for the first pair of rollers 10 and 11, is taken over by the succeeding pair of rollers.

The detachment of the tuft is carried out in a very gentle manner, because (a) the lap 83, having its fibres substantially parallel, offers little resistance to detachment, (b) the detachment is a continuous operation and (c) the roller 36 gives way to a premature detachment (Fig. 9) by moving in the counter clockwise direction.

Preliminary and final combing

Fig. 5 shows the combing cylinder 1 and the two needled segments 86, 87, and 90, 91 in cross section, with a pair of rollers 10 and 11 in different positions around the cylinder, the feeding drum 27 and the receiving drum 46, also being shown in end view as in Fig. 2.

Known machines comprise revolving combing cylinders which carry rows of needles which are thinner and more closely spaced proceeding in the opposite direction to rotation.

In contra-distinction to this usual arrangement, for the preliminary combing of the fibres in the present machine additional rows 87 and 90 of thick and widely-spaced needles are arranged in front of the segments 86 and 91, which have thinner and more closely spaced needles.

Moving onwards from position I, Fig. 5, the pair of rollers 10 and 11 approaches the combing cylinder and reaches the combing position just before position II. In this position the rollers 10 and 11 are revolved around their axes in the directions shown by the arrows and as described above. The end 84 of the tuft penetrates gradually deeper between the needles. The rotation of the rollers lasts for a part or for the whole of the movement of the rollers past the segment 87, thus causing the preliminary combing of the tuft. The needles of the segment 87 working gradually inwards from the tip to near the gripped end of the tuft, prepare the tuft for the succeeding final combing operation. Thus, there is not only a smaller loss of the valuable long fibres and less strain on them, but a greater speed of combing is admissible.

The final combing of the tuft starts at about position III and is finished some time after the rollers 10 and 11 reach position IV during which time the rollers 10 and 11 do not rotate.

By the inversion movement, shown at its culminating position V, Fig. 5, the rollers 10 and 11 are brought into the combing position for the right hand side of the combing cylinder 1 some time before reaching position VI. The uncombed trailing end 92 of the tuft now leads and undergoes a treatment similar to that already described for the originally leading end 84 of the tuft. In position VI, the rollers 10 and 11 (which are now turning on their axes) are shown some time after they have started to feed the tuft to-

wards the combing cylinder. The preliminary combing operation is carried out while the rollers are travelling past the segment 80 and the final combing operation is carried out while they are travelling past the segment 81 and passing position VII.

The percentage of noil is determined by the length of the tuft ends 84 and 92 penetrated by the needles 89 of the combing segments as this length determines the length of the longest fibres and consequently the number of fibres that are combed out. This length can be altered for instance, by changing the number of teeth of the segments 23 and 24, Figs. 3 and 4.

By combing thoroughly both ends of the tuft, the best possible combing of the fibres is achieved.

Overlapping

This operation is similar to the detachment of the tuft but, of course, is carried out in a reverse manner.

Leaving the combing position shortly after position VII, Fig. 5, the rollers 10 and 11 travel downwards towards the delivery drum 46, see position VIII Fig. 5, until, see Fig. 10, the roller 10 comes to rest on the drum 46, and thus upon the end of the combed lap 83 if the machine has been in operation for some time. A part 94 of the bar 17 (Fig. 1) connecting the bearing boxes 16 simultaneously falls into a recess in the arm 55. As described above, the roller 10 rolls on the drum 46 during its succeeding movement around a part of it (Fig. 11) pressing the tuft onto the fibres of the lap 83 and delivering it onto the surface of the drum. Being carried along with the part 94, the arm 55 causes the arm 49a to move in the anti-clockwise direction. In this manner, the roller 38a follows the roller 10 and presses the delivered tuft thoroughly with the lap.

Fig. 12 shows the whole tuft after its delivery a short time earlier, the end 92 of the tuft being underneath the roller 38a. At this moment, the connection between the part 94 and the arm 55 is released by setting the rise 54 of the cam 51 in the right position. The roller 56 passing from the part of the cam 51 of larger radius to the part of smaller radius brings about the release. The arm 49a can now move in the clockwise direction owing to the action of the weight 32a, taking along with it the roller 38a (Fig. 13), while the rollers 10 and 11 finish their movement around the drum 46. The arm 49a comes to a standstill against a stop 48a at some distance from the calender roller 65, Fig. 5, and stays there until the succeeding pair of rollers 10 and 11 reaches the initial position, Fig. 10, for the overlapping operation. The combed lap 83 leaves the delivery drum 46 underneath the calender roller 65 ready for the succeeding spinning operations.

By changing the speed of the delivery drum 46 in relation to that of the feeding drum 27, the length of the "overlap" can be altered. Thus, the thickness of the delivered lap 83 can be influenced within wide limits.

The noil is removed from the combing cylinder 1 by one or more circular brushes in a known manner, but the brush has to rotate round the combing cylinder, as the machine is built with a normally stationary combing cylinder.

Having been removed from the brush the noil can be transported by suction through the hollow shaft 2.

The modified machine shown in Figs. 14, 15 and 19 is particularly useful for combing shorter stapled fibres, which have to be held closer to the combing needles than is possible if they are held between the tuft-holding rollers.

This modified machine is characterised by the feature that after the tuft has been detached from the lap of uncombed fibres by a pair of tuft-holding rollers 10 and 11 it is held between one of said rollers and a nipper means, which is operatively associated with the pair of rollers and is continuously revolved around the combing cylinder or support, the nip of the roller and the nipper means being caused to approach the 15 combing needles and to remain in relatively close proximity to them throughout the combing operation. By this method, the tuft is gripped at a position on the periphery of one of the rollers of the pair of tuft-holding rollers, which is relatively much nearer to the combing needles than the line of contact of the two rollers, so that, obviously, much shorter fibres can be combed.

As in the combing machine described above, 25 the rollers of each pair of tuft-holding rollers 10 and 11 are turnably mounted in two interconnected bearing boxes 16 having outwardly projecting shafts 18, which shafts are also turnable in bearings provided in two supporting bars 21 30 slidable in radial guides fixed on the front and rear discs or end plates 3 of the revolvable carrier member 3, 9. In the machine now being described, however, see Fig. 19, the shafts 18 are extended so as to engage in continuous guide 35 slots formed in the end frames 6 of the machine as described more fully hereinafter.

Further, on each of the said shafts 18 the pin-carrying discs 20 are replaced by two radial arms 20a arranged diametrically (Fig. 19) each carrying 40 a pin and each set of two pins P and S cooperates with guide slots provided on the front and rear end frame members of the machine, as described hereinafter with reference to Fig. 14. These cooperating shafts and slots and the cooperating pins and slots cause each pair of tuft-holding rollers to follow a predetermined path (which differs somewhat from that described above) and to carry out the two inversions 45 movements as they travel through one revolution around the comb support, just as in the machine of Figs. 1 to 13.

This modified method of moving the rollers 10 and 11 is used when movable means, such as a nipper bar, are arranged to operate in association with each pair of tuft-holding rollers, the nipper bar being carried upon supporting means mounted upon, and movable with, the said carrier member 3, or the plate 9. Means are provided whereby the nipper bar is forced into contact with one of said rollers during each time the ends of each tuft are being combed. This arrangement will be more specifically described hereinafter with reference to Fig. 15.

The said modified method for moving the cooperating rollers 10 and 11 around the combing cylinder 1 is shown in Figs. 14 and 19.

The outwardly-extended shafts 18, Fig. 19, take over the work carried out by the pins R and T in the construction of Figs. 1 to 13. Therefore, the discs 20 are not needed in this constructional form and, as mentioned above, they are replaced by radial bars 20a carrying the diametrically opposite pins P and S at equal distances from the 70 centre of the boss which carries the bars and 75

which is fixed to the shaft 18, or parts attached to it.

The chain dotted line in Fig. 14 indicates the centre line of the guide slot cut into each end frame 6, of the machine, Fig. 19, and into which projects the end of shaft 18. When the machine is in operation, the ends of each shaft 18 slide in the guide slots in the two end frames and thus control the position of the rollers 10 and 11 in relation to the centre M, as they travel around the combing cylinder. The turning movement of the rollers around the centre of the cross formed by lines connecting the centres of these pins P and S and the centres of the rollers 10 and 11, is controlled by the pins P and S, one or both of which slides in guide slots 6a provided for them in each end frame 6, Fig. 19, of the machine.

Referring to Fig. 14, in position 0 the pins P rest in the corners of the guide slots 71. As the centre of the above mentioned cross moves away from the feeding drum 27, the pins P are guided in the longer parts of the recesses 71 until position 1 is reached and the pins S have entered the lower ends of guide slots 72. The pins S continue to travel in the guide slots 72 until the positions 2 to 4 are reached and passed. Beyond position 4, as indicated by broken lines, the pins S leave the upper ends of the slots 72 and the pins P enter the top ends of guide slots 107, in which they remain while reaching and passing through the positions 5, 6 and 7. In position 8, the pins P leave the slots 107 while the pins S enter guide slots 81. After position 8 the centre of the said cross moves further along the chain-dotted line and, during the movement of the said cross along that part of the said line which is concentric with the delivery drum 46, the pins S travel in the bottom of the slots 81 and the pins P swing over towards the slots 71. In position 9, the pins S leave the slots 81, while the pins P enter the slots 71 and as the pins advance in these slots the pins S swing upwards. The centre of the said cross moves concentrically around the centre of the feeding drum 27 when the pins P are turning at the junction of the inclined branches of the slots 71.

Fig. 15 shows diagrammatically the combing cylinder 1 and the two needled, preliminary combing segments 87 and 90 and the two needled, final combing segments 86 and 91. The feeding drum 27 and the receiving drum 46 are shown in end view in Figs. 14 and 15.

As shown in the positions 1 to 3, Fig. 15, after the cooperating tuft-holding rollers 10 and 11 have moved from the feeding drum 27, the spacing of the rollers from the centre M of the combing cylinder gradually diminishes. In Fig. 15, position 1, the roller 11 either touches, or approaches very closely to, an arcuate sectioned nipper bar 95, having a rounded leading edge, one such nipper bar being associated with each pair of rollers 10 and 11. Each nipper bar 95 extends between the said front and rear discs or end plates 3 of the carrier member 3, 9, by which the pairs of tuft-holding rollers are revolved around the combing cylinder 1. One disc, i. e., the rear disc 3 only is shown in Fig. 15. The nipper bar is of about the same length as the covered parts of the rollers 10 and 11 and it is fixed at each end to an arm 96, each of the two arms being pivoted at 97 to a lever 98, shown in positions 2 and 5, which is pivotally mounted at 99 on the front or rear disc as the case may be. Each nipper bar 95 is thus supported by two arms 96 carried by two levers 98, arranged at opposite ends

of the said carrier member, the arrangement being such that the bars are carried around the combing cylinder together with the adjacent pair of rollers 10 and 11 with which they are always associated. Each arm 96 is provided with a pin 101, which is adapted to engage in an arcuate slot 102 cut in the adjacent disc 3, or in a part attached thereto, the slot being shown only in positions 2 and 5.

10 The arms 96 are acted upon by springs (indicated by the arrows 100) which are fixed at their opposite ends to the front or rear disc. By this arrangement, as the said discs rotate, the arms 96 tend to turn in the anti-clockwise direction under the action of the springs 100, the pins 101 sliding in the slots 102, see position 5, wherein the pin 101 has moved to the bottom end of the slot 102. The slots 102 are formed in such a way as to keep the nipper bars 95 at the required distance from the rollers 10 and 11.

15 Starting from the position 0, Figs. 14 and 15, during its movement around the combing cylinder 1, the roller 11 either touches, or very closely approaches, the nipper bar 95 when it reaches position 1 as already mentioned above. Not too far removed from position 1, the rollers 10 and 11 are caused to start turning in the direction indicated by the arrows in position 2, thus delivering at least the tips 84 of the tuft past the nipper bar 95. Thereafter, the rollers 10 and 11, or a member operatively connected with them, by further approaching the centre M of the comb support, turn the arms 96 in the clockwise direction against the action of the springs 100, the pins 101 being guided in the slots 102.

20 As a result of the action of the springs 100 and the movement of the rollers 10 and 11, the nipper bar 95 is forced to enter the space between the rollers in position 2. In this manner, the tuft is pressed against the roller 10 by the nipper bar.

25 Assuming that the tuft is so short that only the tips of the tuft end 92 are still held between the rollers 10 and 11, a further turning movement of the rollers will cause the tuft to be gripped solely between the roller 10 and the nipper bar 95, see position 3. If a longer stapled material is used, however, the end 92 of the material will also be gripped between the rollers.

30 In travelling from position 2 to position 3, the rollers 10 and 11 still approach the centre M of the comb support and the arms 96 turn further in the clockwise direction, thereby gradually presenting the end 84 to the needles of the combing segment 87, thus effecting the preliminary combing, until about position 3 is reached.

35 In position 3, Fig. 15, the roller 10 and the nipper bar 95 are at their shortest distances from the needles and this combing position is maintained by the rollers and nipper bar while the tuft is being combed by the needles of the combing segment 87 and until position 4 is reached.

40 Beyond this position, as in the case of the machine described with reference to Figs. 1 to 13, the rollers 10 and 11 are inverted through 180 degrees (but in the clockwise direction) so that the roller 11 then becomes the leading roller. During the first part of this inversionary movement, the distance of the rollers 10 and 11 from the centre M increases and, under the action of the springs 100 and slots 102, the arms 96 turn in the anti-clockwise direction.

45 Meanwhile, the rollers 10 and 11 have turned about their axes in the direction indicated by the dotted arrows in position 4. Thus, the uncombed tuft end 92, if not still under the control of the

rollers 10 and 11, is gripped first between the rollers until, in continuation of this movement, a desired length of the uncombed end protrudes from between the rollers, as shown in position 5. In the manner described in connection with the tuft end 84, in position 4, the end 92 of the tuft is first delivered past the nipper bar 95 (not shown). Position 6 corresponds to position 2, and so on, so that the preliminary-combing and the final combing of the tuft end 92 is carried out in the same way as already described in connection with the end 84. After the rollers 10 and 11 have reached position 8, they move towards the delivery drum 43 until they reach position 0 again and the arms 96 return to their initial positions shown in position 0.

In a modified construction shown in Fig. 15A, just before and during the combing of each end of the tuft, the latter is not gripped between one of the rollers 10 and 11 and the single nipper bar 95, but between the latter and another nipper bar 95A arranged symmetrically to it. The second nipper bar 95A is shown in positions 0 to 5 in Fig. 15A. The nipper bar 95A is carried upon arms 96A, position 5, identical with the arms 96, also pivotally mounted upon levers 98A which are identical with the levers 98 and are pivotally mounted upon the end discs 3 of said carrier member 3, 9. The second nipper bar 95A, however, is directed against the direction of travel of the rollers 10 and 11. The arms 96A carrying the second nipper bar 95A are acted upon by springs 100A corresponding to the springs 100, and the arms also carry pins 101A, corresponding to the pins 101, movable in curved slots 102A.

In this modification, the rollers 10 and 11 gradually approach the centre M of the combing cylinder from position 0, see Fig. 15A, and in position 1 the roller 11 contacts the nipper bar 95 and the roller 10 the second nipper bar 95A. About in this position, the rollers are turned so that they deliver the end 84 of the tuft between the two nipper bars. At the desired moment, in about position 2, the two nipper bars 95 and 95A both enter the space between the rollers and the tuft is gripped between them. The bars continue to approach the centre M, the arms carrying them being pushed inwards towards the centre M by the rollers, or means attached to them, so that they gradually present the tuft end 84 to the needle segment 87 for the preliminary combing. In about position 3, the rollers 10 and 11 have ceased turning, the nipper bars have ceased approaching the centre M and this combing position is maintained during the final combing.

After the final combing, beyond position 4, the nipper bar carrying-arms 96 and 96A are turned outwards again and directed away from the centre M, and the rollers 10 and 11 are turned on their axes and grip the uncombed tuft end 92. The rollers carry out their inversionary movement, position 5, and the same operations of the two nipper bars 95 and 95A are carried out while the tuft end 92 is being combed by the preliminary and final comb sets 90 and 91 on the right hand side of the combing support.

If the tufts are relatively short they may be gripped solely by the nipper bars 95 and 95A during the combing operations, being then released by the rollers 10 and 11, positions 3 and 4. Longer tufts, however, are gripped both by the rollers and the nipper bars.

Figs. 16 and 17 show a modification of the bearing boxes 16 illustrated in Fig. 3a for holding the rollers 10 and 11. This modified construction-

al form serves a dual purpose, viz., it permits the quick removal of the rollers from the boxes 16 and also a better screening of the gears driving the rollers, which gears if fixed outside the boxes 16 near the covered parts of the rollers are more exposed to dust.

In contrast to the construction of Fig. 3a, the slot 15 and the part bearings 13c and 14a in Fig. 16 are wider. These part-bearings are slotted or drilled at 108 at each side to allow a bent rod 109, to be passed through them, the ends of the rods protruding through the bottom part or connecting bar 17 of the boxes 16. On the inner end of the rod 109 is fixed a plate 110 which carries a set screw 111 adapted to adjust the pressure of a spring 112 upon the half-bearing 13c. On both sides of the bent rod 109 there are provided stops 113 which prevent the half-bearing 14a moving outwards. To both outer ends of the bent rod there are fixed two spaced buttons 114, the distance between which is equal to the thickness of the plate 115, see Figs. 16 and 18. The plate is provided with two curved slots 116, and is turnably arranged on a set screw 117, which is screwed into the connecting bar 17 of the boxes 16.

When the machine is operating the position of the rollers and the associated parts described above is as shown in Fig. 16. The plate 115 is locked by virtue of its slots 116 engaging between the buttons 114, thus holding the bent rod 109 within the slot 15 at the desired distance from the bar 17, this distance being adjustable by the screw 117.

When the rollers 10 and 11 have to be taken out of their bearing boxes 16 the machine is stopped and the plates 115 are disengaged from between the buttons 114 although they are still held by the set screw 117 so that they cannot be lost. All the other parts connected with the bent rods 109, including the rollers 10 and 11 and gears 118, Fig. 17, on the shafts of the rollers 10 can be taken out of the boxes by removing the bent rods.

The gears driving the pairs of rollers 10 and 11 can be arranged in different ways. As shown in Figs. 17, 19, and 21 for example, the rollers are adapted to be turned by the turning of a main wheel or gear 122 rotatably mounted on the shaft 18. The gear 122 drives a gear 121 which is fixed at one end of a shaft 120 (Fig. 17) turnable in the end of the box 16, the other end of said shaft carrying a gear 119. The latter drives the gear 118.

Within the opposite box 16 a gear is fixed on the other journal part of the roller 10, in a main wheel or similar position to that of the gear 118, and it engages with another gear fixed on the journal part of the roller 11. These gears are not shown but it will be clear that, by this arrangement, each turning movement of one of the rollers causes the other roller to turn in the opposite direction.

Fig. 19 is a diagrammatic view, similar to Fig. 1, which besides showing the arrangement for the modification of Fig. 14 also shows an arrangement hereinafter to be described and Fig. 21 is a section on the line A—A in Fig. 19. Figs. 19 and 21 show an alternative means for turning the rollers 10 and 11 around their own axes while they are moving around the combing cylinder 1.

Whereas in the machine of Figs. 1 to 13, the rollers 10 are turned by the pressure of their surfaces against the feeding drum 27 and the delivery drum 46, in the modified construction now to be described they are driven positively while travelling past the said drums.

The simplest way of doing this would be to use the gears 12, Figs. 1 and 4, or similar gears, fixed to the rollers 10 near to their covered parts, outside the bearing boxes 16. The said gears could be arranged to mesh with two gears fixed to the shafts 28 and 47 of the feeding and delivery drums when they are travelling around these drums. This solution however, could expose the said gears to the dust which is at its greatest near the combing cylinder.

The arrangement of gears shown in Fig. 17 and partly in Fig. 19, avoids the above mentioned disadvantage to a great extent.

Fig. 21 shows the gears 122 mounted on the shafts 18 in the positions 0 to 3, 7 and 8 which correspond to the positions marked with the same numbers in Fig. 14. In position 8, the gear 122 is about to mesh with the teeth of a gear 124, which is fixed on the shaft 47 of the delivery drum 46. In position 0, the gear 122 meshes with a gear 123, fixed on the shaft 28 of the feeding drum 27. In both of these positions, the gears 122 receive a turning movement in the anti-clockwise direction. The same turning direction is given to the gears 119, Fig. 17, on the journal parts of the rollers 10, through the intermediary of the gears 119 and 121, so that the rollers 10 and 11 revolve in the desired direction.

Whereas, in the machine of Figs. 1 to 13, it is necessary to get sufficient friction between the rollers 10 and the drums 27 and 46 to cause a turning of this roller (Figs. 4, 6 to 8, and 10 to 13), this is unnecessary, if the roller 10 is positively driven by means, such as described above. In this case, it is of advantage to leave some space between the roller 10 and the drums 27 and 46, so that laps which differ greatly in thickness can be used. It is of further advantage that the drums 27 and 46 need not be covered with elastic material, because no pressure is being exerted by the roller 10.

The roller 11, however, has to be brought into the desired position, i. e., scarcely touching the feeding drum 27 and this can be attained by the following methods, or by a combination thereof, viz., by (1) choosing the diameters of the rollers 10 and 11 so as to fulfill the requirements, (2) by setting the rollers 10 and 11 so that the line connecting the centres of the pins P and S crosses the roller 11 instead of roller 10, Figs. 4, and 14, and (3) by abandoning the principle that the lines connecting the centres of the pins P and S and the centres of the rollers 10 and 11 must enclose angles of 90 degrees. If the roller 11 is fixed closer to the feeding drum 27, this roller will be further from the delivery drum 46 when moving round a part of it. This is of advantage because the space between the roller 11 and the lap 93 lying on the drum 46, will increase.

Before describing the further movements of the rollers 10 and 11, the theoretical foundations of the movements of the tuft during the preliminary and final combing operations will be given with reference to Fig. 15.

Shortly after the detachment of the tuft, a short fringe of the tuft end 84 protrudes beyond the nip of the rollers 10 and 11. About up to position 3, where the final combing of the tuft starts, the rollers have to turn through a certain angle which varies with the kind of fibrous material to be combed. As a certain angle of turning of the rollers 10 and 11 is in relation to a fixed length of movement of the tuft such an angle will be taken as a length delivered. The desired angle of turning x of the roller 10 from posi-

tion 0 to position 3 has to be in the anti-clockwise direction and turning in that direction will be indicated by the negative sign, thus $-x$.

After the completion of combing by the comb segment 86, the tuft end 92 (see Fig. 15) has to be nipped again by the rollers 10 and 11 and they are turned deliberately through such an angle as to allow the end 92 to protrude the same distance as the end 84 protruded after the detachment of the tuft. For this purpose, the rollers have to be turned as much as to move the tuft a certain length y , and because the roller 10 has to be turned in the clockwise direction, the sign will be positive, thus $+y$. After the inversion of the tuft, the uncombed tuft end 92 protrudes as mentioned above as far as the tuft end 84 protruded before the combing by the comb segment 87. It is evident that in order to receive the same combing as the end 84, the end 92 has now to be fed the same length x . Up to the point where the final combing by the comb 91 starts, the roller 10 has to be turned through an angle $+x$. After the final combing of the end 92, the roller 10 has to be turned through an angle $-y$, so that in position 8 there is the same protrusion of the tuft end 84 as the protrusion after the detachment of the tuft.

The necessary turning movements of the roller 10 for the above mentioned purposes are therefore: $-x, +y, +x, -y$.

The arrangement for arriving at this result is shown more or less diagrammatically in Figs. 19 and 21.

In one of the discs 3 (see also Fig. 21) there are provided slots serving as guiding and holding means for T-shaped members 125 which operate in association with the, or each pair of rollers 10 and 11. The ends of slides 128, which are slidably arranged in the members 125, are integral with racks 126 and 127 which are caused to engage alternatively with the said gears 122 loosely mounted on the shafts 18 under the action of levers 129. The latter are turnably mounted on the members 125 and are provided at each end with a slot, as diagrammatically shown in Fig. 21. In one of these slots is engaged a pin 132, which is fixed to a lever 131 adapted to swing around a pin 130 fixed to the member 125. Guided in the other slot in the lever 129, there is a pin 133 fixed on the slide 128. Thus, when the lever 131 is moved in the clockwise direction to the extreme position shown in Fig. 21, position 1, the rack 126 meshes with the gear 122. When the lever 131 is turned in the anti-clockwise direction, however, the gear 122 is disengaged from the rack 126 and then meshes with the rack 127, see position 7 in Fig. 21.

Between the combing cylinder 1 and the disc 3, Figs. 19 and 21, a stationary disc 134 is fixed on the stationary main shaft 2. The side of the disc 134 adjacent to the disc 3 is provided with a guide slot 135, in which runs a roller 136 mounted on a pin 137 which is fixed on the member 125. While moving around the combing cylinder 1, the roller 136 slides in the slot 135 and causes the member 125 to follow the path of the slot.

As shown in Fig. 21, at position 1, the inner arm of the lever 131 just has passed a stationary pin 138 which is fixed in the disc 134 and has caused the lever 131 to move in the clockwise direction. The gear 122, meshing with the rack 126, starts turning in the anti-clockwise direction as the shaft 18 follows the ascending chain dotted path, and so the turning movement $-x$ of the roller 10 commences. From position 2

onwards the said path does not ascend steeply enough, so that the slot 135 is steepened in order to cause the gear 122 to be turned through a sufficient angle. From about position 3 onwards, when the final combing starts, the gear 122 does not require to be turned and in order that there shall be no relative movement between the gear 122 and the rack 126, the slot 135 is concentric with the chain dotted path.

After the final combing by the comb segment 86, the chain dotted path rises, see Fig. 14, and its ascent can be coupled with the descent of the guide slot 135. This causes the gear 122 to turn through a positive angle. After this turning movement (through the angle $+y$) has been concluded, the gear 122 moves out of mesh with the rack 126, the outer arm of the lever 131 striking a stationary pin (not shown) on the disc 134 which causes the lever to turn to the anti-clockwise direction.

The turning movement $+x$ and $-y$ are imparted to the roller 10 on the right hand side of the combing cylinder 1 in a similar manner, but in order to arrive at the required reverse directions of turning, the rack 127 is caused to engage with the gear 122, see position 7 in Fig. 21.

The turning angles of the roller 10 depend upon the number of teeth of the racks 126 and 127 which mesh with the gear 122. The later the pin 138 or its corresponding pin 141 on the righthand side of the combing cylinder 1 causes the racks to mesh with the gear 122, the smaller will be the turning movement x . The pins which cooperate with the levers 131 on the right and left hand sides of the combing cylinder can be so arranged that any practical turning angles x and y can be arrived at.

It is advantageous to interconnect the corresponding pins on the right and left hand sides of the combing cylinder so that when the pins on the left hand side are adjusted for the desired turning movements $-x$ and $+y$, the pins on the right hand side are adjusted simultaneously for the desired turning movements $+x$ and $-y$.

As already mentioned, the pins must be stationary, and it is advantageous to fix them on the stationary disc 134, or on parts attached to it.

In Fig. 21 the number of needled rows is increased so that they reach beyond the zones where the actual combing is being carried out (i. e., approximately between the positions 2 to 4, Fig. 15, for the left hand side). The reason for this arrangement is to influence the percentage of the comber waste, by bringing into the zone either more needled rows with closer, or more needled rows with wider spaced needles. By turning the combing cylinder through a certain angle in the clockwise direction, more of the coarser needles will be engaged, causing a lesser percentage of noil. The reverse effect is achieved by turning the combing cylinder in the anti-clockwise direction, so that, within practical limits, any percentage of noil can be arrived at by setting the combing cylinder in the right way.

In order to hold the combing cylinder 1 for the aforesaid purpose in any required position, the side of the cylinder 1 adjacent to the disc 134 is provided with holes 134a (Fig. 20), arranged on a circle concentric to the main shaft 2. On the same diameter the disc 134 carries a pin 145, provided with a shoulder 144 near its inner end, which latter is adapted to engage in the said holes. At its opposite end the pin 145

is provided with a knob and a spring 143 presses against the shoulder 144 and holds the pin 145 in one of the holes, thus fixing the combing cylinder. For setting the cylinder in a different position, the knob is pulled, the combing cylinder is turned into the required position, and the knob is released, when the pin 145 is opposite a hole 134a in the combing cylinder.

The distances between the needled rows can be increased. By this arrangement less strain is imposed on the fibres (which gives a stronger product, and permits a greater combing speed) because the fibres are not drawn through several combs at the same time. Especially when combing longer stapled fibres, and while drawing them through the last and closely set needles, this strain is considerable.

Although reference has been made above to the use of two cooperating tuft holding rollers, 20 it is understood that the term "rollers" includes other rotatable members such as cooperating quadrants, part drums, or part cylinders or arms or bars having curved cooperating peripheries and these may be different from each other, and 15 may number more than two.

It will be understood that the methods and 25 machines according to this invention may be used for combing cotton, wool, silk and other fibres used in textile industry.

30 I claim:

1. A machine for combing cotton and other textile fibres, comprising a rotatable lap-feeding drum, a rotatable combed lap delivery drum, a stationary combing means arranged between said drums, two spaced segmental needle sets on said combing means, a carrier member coaxial with said combing means adapted to revolve around the latter, a plurality of pairs of cooperating, parallel tuft-holding rollers, means for holding 35 said rollers of each pair of rollers in contact, means for supporting each of said pairs of rollers on said carrier member with their axes parallel to its axis and in such a manner that said rollers are caused to revolve around said combing means 40 and can also move radially towards and from the axis of said carrier member, said means including turnable bearing members in which the opposite ends of the two rollers are journalled and in which said rollers can move in a plane passing 45 through the longitudinal axes of said rollers, means for causing each cooperating pair of bearing members to carry out turning movements periodically during a complete revolution of said carrier member and so as to invert said rollers as 50 a unit and make that roller which has led the pair of rollers when travelling past said feeding drum, and past the first segmental needle set to become the trailing roller when said rollers are moving past the second segmental needle set 55 and past said delivery drum, means for causing said rollers to rotate about their axes as they are travelling past a portion of the length of the first needle set so as to present part of the tuft thereto, said rollers remaining stationary on their axes 60 when they are travelling past the remainder of the first needle set, and means for causing said rollers to rotate about their axes as they are travelling past a portion of the length of the second needle set so as to present the remainder 65 of the tuft thereto, said rollers remaining stationary on their axes when they are travelling past the remainder of the second needle set.
2. The combination set forth in claim 1, wherein in said combing means is fixed upon a stationary main shaft mounted in spaced front and rear

frame members and said carrier member comprises two interconnected end plates rotatably arranged upon said shaft at opposite ends of said combing means, and wherein said means for supporting each of said pairs of cooperating rollers consists of guide members fixed radially respectively to the front and the rear end plate and supporting bars slideable radially in said guide members, the two bearing members in which the opposite ends of the two cooperating rollers are journaled consisting of two interconnected bearing boxes which are turnably supported respectively in bearings on the two bars.

3. The combination set forth in claim 1, wherein said combing means is fixed upon a stationary shaft mounted in spaced front and rear frame members and said carrier member comprises two interconnected end plates rotatably arranged upon said shaft at opposite ends of said combing means, and wherein said means for supporting each of said pairs of cooperating rollers consists of guide members fixed radially respectively to the front and the rear end plate and supporting bars slideable radially in said guide members, the two bearing members in which the opposite ends of the two cooperating rollers are journaled consisting of two interconnected bearing boxes which are turnably supported respectively in bearings on the two bars, said bearing boxes having slots in which the roller ends are journaled so that said rollers can slide in said boxes in a plane passing through the axes of said rollers.

4. The combination set forth in claim 1, wherein the percentage of noil can be altered by adjusting said combing means so as to vary the number of needles engaged by the tuft.

5. The combination set forth in claim 1, wherein said combing means is fixed upon a stationary main shaft mounted in spaced front and rear frame members and said carrier member comprises two interconnected end plates rotatably arranged upon said shaft at opposite ends of said combing means, and wherein said means for supporting each of said pairs of cooperating rollers consists of substantially radial guide members fixed respectively to the front and the rear end plate and supporting members slideable substantially radially in said guide members, the two bearing members in which the opposite ends of the two cooperating rollers are journaled consisting of two interconnected bearing boxes which are turnably supported respectively in bearings on the two supporting members, and wherein each of the two interconnected bearing boxes rotatably supporting one end of each of two cooperating rollers has fixed thereto a shaft turnably supported in one of said supporting members, and wherein a member is fixed to each shaft and is provided with a set of pins adapted to cooperate with guiding means on the adjacent frame member, the cooperation of the two sets of pins with their respective guiding means being adapted to cause the bearing boxes to turn about the axes of their shafts and to cause the pair of cooperating rollers, the two interconnected bearing boxes, the shafts of the latter and the two supporting members carrying the shafts to move toward and away from the axis of the shaft upon which said carrier member is turnably mounted.

6. The combination set forth in claim 1, wherein said combing means is fixed upon a stationary main shaft mounted in spaced front and rear frame members and said carrier member comprises two interconnected end plates rotatably arranged upon said shaft at opposite ends of said

combing means, and wherein said means for supporting each of said pairs of cooperating rollers consists of substantially radial guide members fixed respectively to the front and the rear end plate and supporting members slideable in said guide members, the two bearing members in which the opposite ends of the two cooperating rollers are journaled consisting of two interconnected bearing boxes which are turnably supported respectively in bearings on the two supporting members, and wherein each of the two interconnected bearing boxes rotatably supporting one end of each of two cooperating rollers has fixed thereto a shaft turnably supported in one of said supporting members, and wherein a member is fixed to each shaft and is provided with a set of at least two pins said pins being adapted to cooperate with guiding means on the adjacent frame member, each of said guiding means being adapted to engage said pins in succession as said carrier member revolves, the cooperation of each set of pins with its respective guiding means being adapted to cause the bearing boxes to turn about the axes of their shafts and to cause the pair of cooperating rollers, the two interconnected bearing boxes, the shafts of the latter and the two supporting members carrying the shafts to move toward and away from the axis of the shaft upon which said carrier member is turnably mounted.

7. The combination set forth in claim 1, wherein said combing means is fixed upon a stationary main shaft mounted in spaced front and rear frame members and said carrier member comprises two interconnected end plates rotatably arranged upon said shaft at opposite ends of said combing means, and wherein said means for supporting each of said pairs of cooperating rollers consists of substantially radial guide members fixed respectively to the front and the rear end plate and supporting members slideable substantially radially in said guide members, the two bearing members in which the opposite ends of the two cooperating rollers are journaled consisting of two interconnected bearing boxes which are turnably supported respectively in bearings on the two supporting members, and wherein each of the two interconnected bearing boxes rotatably supporting one end of each of two cooperating rollers has fixed thereto a shaft supported in one of said supporting members, and wherein a member is fixed to each shaft and is provided with a set of pins adapted to cooperate with guiding means on the adjacent frame member, the cooperation of each set of pins with its respective guiding means being adapted to cause the bearing boxes to turn about the axes of their shafts and to cause the pair of cooperating rollers, the two bearing boxes, the shafts of the latter and the two supporting members carrying the shafts to move toward and away from the axis of the shaft upon which said carrier member is turnably mounted, and wherein each of the said frame members is provided with guide tracks with which at least two pins at a time of said set of pins on the pin supports of each pair of cooperating pin supports are adapted to cooperate so as to hold the two supporting members and the bearing boxes against rotation on their axes while the two ends of the tuft are being combed respectively by the first and second segmental needle sets.

8. The combination set forth in claim 1, wherein said combing means is fixed upon a stationary main shaft mounted in spaced front and rear frame members and said carrier member com-

prises two interconnected end plates rotatably arranged upon said shaft at opposite ends of said combing means, and wherein said means for supporting each of said pairs of co-operating rollers consists of substantially radial guide members fixed respectively to the front and the rear end plate and supporting members slideable in said guide members, the two bearing members in which the opposite ends of the two co-operating rollers are journaled consisting of two interconnected bearing boxes which are turnably supported respectively in bearings on the two supporting members, and wherein each of the two interconnected bearing boxes rotatably supporting one end of each of two co-operating rollers has fixed thereto a shaft turnably supported in one of said supporting members, and wherein a member is fixed to each shaft and is provided with a set of at least two pins said pins being adapted to co-operate with guiding means on the adjacent frame member, each of said guiding means being adapted to engage said pins in succession as said carrier member revolves, the co-operation of each set of pins with its respective guiding means being adapted to cause the bearing boxes to turn about the axes of their shafts and to cause the pair of co-operating rollers, the two interconnected bearing boxes, the shafts of the latter and the two supporting members carrying the shafts to move toward and away from the axis of the shaft upon which said carrier member is turnably mounted, together with means for pressing the lap down onto said feeding drum, means for moving said pressing down means temporarily in the direction and at the speed of the movement of said feeding drum, means associated with said co-operating pair of rollers for moving said pressing down means temporarily in the opposite direction and means for moving said pressing down means at a speed exceeding that of the feeding drum to the end of the lap.

9. The combination set forth in claim 1, wherein said combing means is fixed upon a stationary main shaft mounted in spaced front and rear frame members and said carrier member comprises two interconnected end plates rotatably arranged upon said shaft at opposite ends of said combing means, and wherein said means for supporting each of said pairs of co-operating rollers consists of substantially radial guide members fixed respectively to the front and the rear end plate and supporting members slideable in said guide members, the two bearing members in which the opposite ends of the two co-operating rollers are journaled consisting of two interconnected bearing boxes which are turnably supported respectively in bearings on the two supporting members, and wherein each of the two interconnected bearing boxes rotatably supporting one end of each of two cooperating rollers has fixed thereto a shaft turnably supported in one of said supporting members, and wherein a member is fixed to each shaft and is provided with a set of at least two pins said pins being adapted to co-operate with guiding means on the adjacent frame member, each of said guiding means being adapted to engage said pins in succession as said carrier member revolves, the co-operation of each set of pins with its respective guiding means being adapted to cause the bearing boxes to turn about the axes of their shafts and to cause the pair of co-operating rollers, the two interconnected bearing boxes, the shafts of the latter and the two supporting members carrying the shafts to move toward and away from the axis of the shaft upon

which said carrier member is turnably mounted, together with turnable means associated with said delivery drum for pressing upon the lap of combed fibres on said drum the combed tuft deposited by each pair of co-operating rollers, means associated with said pair of rollers to cause said pressing down means to follow the trailing roller of said pair of rollers and means causing said pressing down means to return to its initial position after the combed tuft has been deposited on said delivery drum.

10. The combination set forth in claim 1, including nipper means consisting of nipper members, each of said nipper members being associated with a pair of the co-operating tuft-holding rollers and supporting means consisting of a pair of movable carrier members upon which said rollers are mounted, and means whereby said nipper member is forced into contact with one of said rollers as said pair of rollers moves past said combing means.

11. The combination set forth in claim 1, wherein said combing means is fixed upon a stationary main shaft mounted in spaced front and rear frame members, and said carrier member comprises two interconnected end plates rotatably arranged upon said shaft at opposite ends of said combing means, and wherein said means for supporting each of said pairs of co-operating rollers consists of substantially radial guide members fixed respectively to the front and rear end plates and supporting members slideable substantially radially in said guide members, the two bearing members in which the opposite ends of the two cooperating rollers are journaled consisting of two interconnected bearing boxes which are turnably supported respectively in bearings on the two supporting members, wherein each of said two interconnected bearing boxes rotatably supporting one end of each of the two cooperating rollers is provided with a shaft turnably supported in one of said supporting members, and wherein a member is fixed to each shaft and is provided with pins adapted to cooperate with guiding means on the adjacent frame member, and wherein each of said shafts is engaged in a continuous guide slot formed in the adjacent frame member, the movement of the ends of said shafts in said continuous slots being adapted to cause the pair of cooperating rollers, the means for holding said rollers in contact, the positive driving means of said rollers, the said interconnected bearing boxes, the shafts of the latter and the two supporting members carrying the shafts to move toward and away from the axis of the shaft upon which the carrier member is turnably mounted, and wherein the cooperation of the two sets of said pins with their respective guiding means is adapted to cause the pair of cooperating rollers, the means for holding said rollers in contact, the positive driving means of said rollers, and the said two interconnected bearing boxes to turn about the axes of the two shafts fixed to said bearing boxes and turnably supported in said supporting members.

12. The combination set forth in claim 1, wherein said means for holding said rollers in contact consists of part bearings in which the journal ends of said rollers are journaled, said part bearings being arranged in said bearing members and interconnected by means removably mounted in said bearing members in such a manner that they can be easily loosened and removed, whereby the part bearings and said rollers journaled therein can be removed.

13. The combination set forth in claim 1, wherein said combing means is fixed upon a stationary main shaft mounted in spaced front and rear frame members and said carrier member comprises two interconnected end plates rotatably arranged upon said shaft at opposite ends of said combing means, and wherein said means for supporting each of said pairs of co-operating rollers consists of substantially radial guide members fixed respectively to the front and the rear end plate and supporting members slideable in said guide members, the two bearing members in which the opposite ends of the two co-operating rollers are journaled consisting of two interconnected bearing boxes which are turnably supported respectively in bearings on the two supporting members, and wherein each of the two interconnected bearing boxes rotatably supporting one end of each of two cooperating rollers has fixed thereto a shaft turnably supported in one of said supporting members, and wherein a member is fixed to each shaft and is provided with a set of at least two pins said pins being adapted to co-operate with guiding means on the adjacent frame member, each of said guiding means being adapted to engage said pins in succession as said carrier member revolves, the co-operation of each set of pins with its respective guiding means being adapted to cause the bearing boxes to turn about the axes of their shafts and to cause the pair of co-operating rollers, the two interconnected bearing boxes, the shafts of the latter and the two supporting members carrying the shafts to move toward and away from the axis of the shaft upon which said carrier member is turnably mounted, together with gear wheels for positively turning said rollers, a main gear wheel adapted to drive the other gear wheels, the said main wheel being mounted on said bearing box and means for driving said main gear wheel.

14. A method of combing cotton and other textile fibres, comprising the steps of gripping and detaching a tuft from an advancing lap of fibrous material, moving said tuft by rolling action and presenting one free end thereof for combing, combing said free end of said tuft whilst moving said tuft, inverting said tuft whilst still gripped by rotating it about an axis intermediate its ends, moving said gripped tuft by rolling action and presenting the other end of said tuft for combing, combing said other end whilst moving said tuft, and delivering said tuft onto a lap of previously combed fibres.

15. A method of combing cotton and other textile fibres comprising the steps of advancing a lap of fibrous material to feeding position, gripping one end of said lap, taking a tuft of fibres from said lap while holding said lap in feeding position, drawing the free end of said tuft through a stationary combing means, inverting the partially combed tuft by rotating it about an axis intermediate its ends so that the uncombed end of said tuft is the free end, drawing the uncombed end of said tuft through a stationary combing means and advancing the combed tuft to the delivery position.

16. A machine for combing cotton and other textile fibres including in combination movable feeding means for advancing a lap of fibrous material to a feeding position, stationary combing means, means for receiving combed tufts at a delivery position, at least one pair of rotatable tuft-gripping members having curved cooperating peripheries defining a nip therebetween, means for moving said rotatable tuft-gripping

members from the feeding position and around said combing means to the delivery position and back to the feeding position, means for rotating said rotatable tuft-gripping members about their own axes to grip a tuft from an advancing lap at the feeding position, to move the tuft relative to the nip of said members at an intermediate position and to release the tuft from said nip to said tuft receiving means at the delivery position, and means for controlling the position of said rotatable tuft-gripping members relative to said combining means during travel therearound so as to cause said rotatable tuft-gripping members to approach said combing means in order that the end of the tuft shall be gradually presented to said combining means and to move away from said combining means after the one end of the tuft has been combed during travel from the feeding position to the intermediate position and so as to cause said rotatable tuft-gripping members to approach said combing means in order that the opposite end of the tuft shall be gradually presented to said combining means and to move away from said combining means after the said opposite end of the tuft has been combed during travel from the intermediate position to the delivery position.

17. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said tuft receiving means at the delivery position by appropriate rotation of said tuft-gripping members, at least one nipper means associated with each pair of rotatable tuft-gripping members, means for moving said nipper means relative to said combing means while the associated pair of rotatable members are moving and to move said nipper means toward and away from at least one of said rotatable tuft-gripping members to grip the tuft between said nipper means and said rotatable tuft-gripping member, means for moving said rotatable tuft-gripping members from the feeding position and around said combing means to the delivery position and back to the feeding position, and means for controlling the position of said tuft-gripping members and said nipper means relative to said combing means during travel therearound whereby one end of a tuft gripped by said nipper means and one of said rotatable tuft-gripping members is presented to said combing means during travel from the feeding position to an intermediate position and whereby the opposite end of the tuft gripped by said nipper means and one of said rotatable tuft-gripping members is presented to said combing means during travel from the intermediate position to the delivery position.

18. A machine for combing cotton and other textile fibres including in combination movable feeding means for advancing a lap of fibrous material to a feeding position, combing means, means for receiving the combed tufts at a delivery position, at least one movable pair of rotatable tuft-gripping members having curved cooperating peripheries defining a nip therebetween, means for rotating said rotatable tuft-gripping members about their own axes to grip a tuft from an advancing lap, to move the tuft relative to the nip of said member and to release the tuft

to said receiving means at the delivery position, at least one pair of nipper means associated with each pair of said rotatable tuft-gripping members, means for moving said nipper means along said combing means with the associated pair of rotatable tuft-gripping members, means for moving said pair of nipper means relative to each other and to said associated pair of members to grip the tuft, means for moving said rotatable tuft-gripping members from the feeding position and around said combing means to the delivery position and back to the feeding position, and means for controlling the position of said tuft-gripping members and said nipper means relative to said combing means during travel therearound whereby one end of the tuft gripped by said nipper means is presented to said combing means during travel from the feeding position to an intermediate position and whereby the opposite end of the tuft gripped by said nipper means is presented to said combing means during travel from the intermediate position to the delivery position.

19. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween, means for moving said rotatable tuft-gripping members from the feeding position and around said combing means to the delivery position and back to the feeding position, means causing said rotatable tuft-gripping members to rotate about their own axes in opposite directions, whereby the leading member rotates over a lap lying on said feeding means and the trailing member lightly touches said lap feeding means so as to pick up the end of the lap after said leading member has moved over it and to lead said end between said members, means for pressing the lap down to the feeding means, means to move said pressing down means in the direction in which said members are moving, said rotatable tuft-gripping members being adapted to move the tuft relative to the nip between said members and to discharge the tuft from said nip to said receiving means at the delivery position by appropriate rotation of said members, and means for controlling the position of said rotatable tuft-gripping members relative to said combing means during travel therearound whereby one end of a tuft gripped by said members is presented to said combing means during travel from the feeding position to an intermediate position and whereby the opposite end of the tuft still gripped by said members is presented to said combing means during travel from the intermediate position to the delivery position.

20. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said receiving means at the delivery position by appropriate rotation of said tuft-gripping members, means for moving said rotatable tuft-gripping members from the feeding position and around said combing means to the delivery position and back to the feeding position, means for controlling the position of said tuft-gripping members relative to said combing means during travel therearound, means for causing said rotatable tuft-gripping members to turn about their axes in opposite directions so as to present one end of

livery position and back to the feeding position, means including said last mentioned means to cause said rotatable tuft-gripping members to move away from said lap feeding means with one end of a tuft gripped firmly between said members so as to detach the tuft from the lap, means for pressing the lap down onto said lap feeding means, means for pulling said lap pressing down means to assist in the tuft detaching operation, said pulling means causing said pressing down means to advance to the end of the lap after the tuft has been detached therefrom, and means for controlling the position of said tuft-gripping members relative to said combing means during travel therearound whereby one end of the tuft gripped by said members is presented to said combing means during travel from the feeding position to an intermediate position and whereby the opposite end of the tuft is presented to said combing means during travel from the intermediate position to the delivery position.

21. A machine for combing cotton and other textile fibres including in combination movable feeding means for advancing a lap of fibrous material to a feeding position, a stationary combing means, said combing means comprising a first segment of needled rows for preliminary combing and a second segment of needled rows for final combing, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said tuft receiving means at the delivery position by appropriate rotation of said tuft-gripping members, means for moving said rotatable tuft-gripping members from the feeding position and around said combing means to the delivery position and back to the feeding position, means for controlling the position of said tuft-gripping members relative to said combing means during travel therearound, and means to cause said rotatable tuft-gripping members to rotate in opposite directions as said members are moved past said segment for preliminary combing so that the end of the tuft directed toward said combing means is gradually presented to said first segment of needled rows.

22. A machine for combing cotton and other textile fibres including in combination movable feeding means for advancing a lap of fibrous material to a feeding position, a stationary combing means, said combing means comprising two sets of needled rows, each set comprising one segment for preliminary combing and one segment for final combing, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said tuft receiving means at the delivery position by appropriate rotation of said tuft-gripping members, means for moving said rotatable tuft-gripping members from the feeding position and around said combing means to the delivery position and back to the feeding position, means for controlling the position of said tuft-gripping members relative to said combing means during travel therearound, means to cause said rotatable tuft-gripping members to turn about their axes in opposite directions so as to present one end of

the tuft to said first set of needled rows as said members are moved therewith, means forming a part of said position controlling means for inverting said tuft-gripping members so that the other end of the tuft is directed toward said second set of needled rows, and means to cause said rotatable tuft-gripping members to turn about their axes in opposite directions so as to present the other end of the tuft to said second set of needled rows as said tuft-gripping members are moved therewith.

23. A machine for combing cotton and other textile fibres including in combination movable feeding means for advancing a lap of fibrous material to a feeding position, combing means, at least one pair of rotatable tuft-gripping members having curved cooperating peripheries defining a nip therebetween adapted to grip a tuft from an advancing lap, to move the tuft relative to said nip and to discharge the tuft from said nip by appropriate rotation of said tuft-gripping members, means for receiving the combined tufts at a delivery position, said tuft receiving means including continuously revolving means onto which each succeeding tuft is deposited after combing so as to overlap the preceding tuft of combed material, means to press down said combed tuft on the lap of previously combed fibres, and means associated with said rotatable tuft-gripping members for actuating said tuft pressing down means and to permit said last mentioned means thereafter to return to the initial position, means for moving said rotatable tuft-gripping members from the feeding position and around said combing means to the delivery position and back to the feeding position, and means for controlling the position of said tuft-gripping members relative to said combing means during travel therearound whereby one end of the tuft gripped by said member is presented to said combing means during travel from the feeding position to an intermediate position and whereby the opposite end of the tuft still gripped by said members is presented to said combing means during travel from the intermediate position to the delivery position.

24. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween, means for moving said rotatable tuft-gripping members from the feeding position and around said combing means to the delivery position and back to the feeding position, at least one pivoted nipper means associated with each pair of rotatable tuft-gripping members and movable relative to said members, means causing said tuft-gripping members to rotate periodically about their own axes in opposite directions, means causing said members to detach a tuft from the lap of uncombed fibres, said nipper means being adapted to nip the tuft while said members are rotating in one direction and to lead the advancing tuft so as to present one free end of the tuft to said combing means and to retract the tuft from said combing means after the combing operation by leading the tuft to said pair of rotatable tuft-gripping members while the latter are rotating in the opposite direction, means for controlling the position of said tuft-gripping members and said nipper means relative to said combing means during

travel therearound whereby one end of the tuft is presented to said combing means during travel from the feeding position to an intermediate position and whereby the opposite end of the tuft is presented to said combing means during travel from the intermediate position to the delivery position, and means causing said rotatable tuft-gripping members to discharge the combed tuft to said receiving means at the delivery position by appropriate rotation of said members.

25. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said tuft receiving means at the delivery position by appropriate rotation of said tuft-gripping members, carrier means upon which said rotatable tuft-gripping members are mounted, at least one nipper means associated with each pair of rotatable tuft-gripping members, said nipper means consisting of a nipper bar supported at each end upon an arm pivotally connected to a lever, means pivotally mounting said lever upon said carrier means, spring means pulling each arm and said nipper bar toward said rotatable tuft-gripping members, pins carried by said arms and engageable in slots formed in said carrier means to keep said nipper bar at the required distance from said rotatable tuft-gripping members, the arrangement being such that said spring means forces said nipper bar into contact with one of said rotatable tuft-gripping members during the time the ends of a tuft are being combed, means including said carrier means for moving said rotatable tuft-gripping members from the feeding position and around said combing means to the delivery position and back to the feeding position, and means for controlling the position of said tuft-gripping members and said nipper bar relative to said combing means during travel therearound whereby one end of the tuft is presented to said combing means during travel from the feeding position to an intermediate position and whereby the opposite end of the tuft is presented to said combing means during travel from the intermediate position to the delivery position.

26. A machine for combing cotton and other textile fibres including in combination movable feeding means for advancing a lap of fibrous material to a feeding position, combing means, means for receiving combed tufts at a delivery position, at least one pair of rotatable tuft-gripping members having curved cooperating peripheries defining a nip therebetween adapted to grip a tuft from an advancing lap, to move the tuft relative to said nip and to discharge the tuft from said nip to said tuft receiving means at the delivery position by appropriate rotation of said tuft-gripping members, means for moving said rotatable tuft-gripping members from the feeding position and around said combing means to the delivery position and back to the feeding position, a pair of pivotal nipper means associated with each pair of rotatable tuft-gripping members, said nipper means gripping the tuft when it is being moved along said combing means so that both ends of said tuft may be combed, said nipper means being moved in company to

operate in conjunction with said rotatable tuft-gripping members, said nipper means being adapted to take over the tuft from its adjacent pair of rotatable tuft-gripping members in order to present both ends in succession to said combing means and also to return the tuft to said rotatable tuft-gripping members first after one end of the tuft has been combed and then after the opposite end has been combed, and means for controlling the position of said tuft-gripping members and said nipper means relative to said combing means during travel therearound whereby one end of the tuft gripped by said nipper means is presented to said combing means during travel from the feeding position to an intermediate position and whereby the opposite end of the tuft gripped by said nipper means is presented to said combing means during travel from the intermediate position to the delivery position.

27. A machine for combing cotton and other textile fibres including in combination main driving means, movable feeding means for advancing a lap of fibrous material to a feeding position, said feeding means comprising continuously revolving means operatively connected to said main driving means, combing means, at least one pair of rotatable tuft-gripping members having curved cooperating peripheries defining a nip therebetween adapted to grip a tuft from an advancing lap, to move the tuft relative to said nip and to discharge the tuft from said nip by appropriate rotation of said tuft-gripping members, means for receiving combed tufts at a delivery position said receiving means comprising continuously revolving means operatively connected to said main driving means and onto which the combed tuft

is deposited with each succeeding tuft overlapping the preceding tuft, means driven by said main driving means for moving said rotatable tuft-gripping members from the feeding position and around said combing means to the delivery position and back to the feeding position, means for varying the speed of said feeding means relative to said main driving means so as to vary the lengths of the detached tufts, means for varying the relative speeds of said feeding means and said receiving means so as to vary the lengths of the overlaps of the tufts on said receiving means, and means for controlling the position of said tuft-gripping members relative to said combing means during travel therearound whereby one end of the tuft gripped by said members is presented to said combing means during travel from the feeding position to an intermediate position and whereby the opposite end of the tuft still gripped by said members is presented to said combing means during travel from the intermediate position to the delivery position.

FREDERICK RAUBITSCHEK.
